Primary Examiner — Jae Liang*(74) Attorney, Agent, or Firm* — Sterne, Kessler, Goldstein & Fox P.L.L.C.(57) **CLAIM**

The ornamental design for a spout, as shown and described.

DESCRIPTION

FIG. 1 is a top front perspective view of a spout showing our new design;

FIG. 2 is a top rear perspective view of the spout shown in FIG. 1;

FIG. 3 is a front view of the spout shown in FIG. 1;

FIG. 4 is a rear view of the spout shown in FIG. 1;

FIG. 5 is a right side view of the spout shown in FIG. 1;

FIG. 6 is a left side view of the spout shown in FIG. 1;

FIG. 7 is a top view of the spout shown in FIG. 1; and,

FIG. 8 is a bottom view of the spout shown in FIG. 1.

The broken lines in the drawings depict environmental subject matter only and form no part of the claimed design. The dash-dotted lines in the drawings represent the bounds of the claim and form no part of the claimed design.
